CLAIM

The ornamental design for a food container, as shown and described.

DESCRIPTION

FIG. 1 is a top perspective view of a food container, showing our new design.

FIG. 2 is a front elevation view of the food container of FIG. 1.

FIG. 3 is a rear elevation view of the food container of FIG. 1.

FIG. 4 is a left side elevation view of the food container of FIG. 1.

FIG. 5 is right side elevation view of the food container of FIG. 1.

FIG. 6 is a top plan view of the food container of FIG. 1; and, FIG. 7 is an exploded view of the food container of FIG. 1. The even dashed broken lines in the drawings depict portions of the food container that form no part of the claimed design.

The dash-dot broken lines in the drawings define the bounds of the claimed design and form no part thereof.
